UNITED STATES PATENT OFFICE.

ERNEST JOSEPH BRASSEUR, OF CHICAGO, ILLINOIS, ASSIGNOR TO A. B. DICK COMPANY, OF CHICAGO, ILLINOIS, A CORPORATION OF ILLINOIS.

CONTROL MECHANISM FOR INTERLEAVING DUPLICATING MACHINES.

Application filed September 3, 1927. Serial No. 217,312.

The invention relates to control mechanisms for interleaving duplicating machines, that is, duplicating machines provided with means for delivering printed sheets successively, means for holding a stack or collection of separators or blotters, and means for placing a separator on each delivered sheet to hold the printing thereon from contact with the next succeeding sheet. One object of the invention is to prevent the operation of the sheet delivery means on the exhaustion of separators to avoid the piling up of printed sheets without separators interposed between adjacent sheets. Another object of the invention is to prevent the operation of the separator placing means when no sheet is in position to be fed into and delivered by the sheet delivery means. A further object of the invention is to provide an interleaving duplicating machine with means for preventing the operation of the interleaving devices to permit the machine to deliver printed sheets without the interposition of separators between them. Other objects incidental to the accomplishment of the foregoing objects will appear as the description of the invention proceeds. To these ends the invention consists in the novel mechanism hereinafter described and particularly pointed out in the appended claims.

In the accompanying drawings illustrating the preferred form of the invention, Fig. 1 is an elevation of one side of a known duplicating machine provided with interleaving devices, and showing the attachment of the control mechanism thereto; Fig. 2 is an elevation of the side of the machine opposite to that shown in Fig. 1; Fig. 3 is a top plan of the arrangement of parts shown in Fig. 2; Fig. 4 is an end elevation on an enlarged scale looking from the left in Fig. 2; Fig. 5 is an enlarged section taken on the line 5—5 of Fig. 3; Fig. 6 is an enlarged detail elevation of the interleaving devices shown at the left hand end of Fig. 2, and showing a part of the control mechanism; Fig. 7 is a fragment of the upper part of Fig. 6, showing certain of the members in a different position; Fig. 8 is a partial side elevation of the parts of the control mechanism associated with the sheet delivering devices of the duplicating machine; Figs. 9 and 10 are details of the lock for preventing the operation of the sheet delivery means on the exhaustion of separators, Fig. 9 showing the position of the parts on the exhaustion of separators, and Fig. 10 showing the position of the parts during normal operation of the interleaving devices; Fig. 11 is an enlarged sectional elevation of the essential parts of the sheet delivery means of the duplicating machine to illustrate the cooperation of certain parts of the control mechanism therewith; Fig. 12 is a view similar to Fig. 11, but taken from the opposite side of the machine; Fig. 13 is a detail of the means for raising and lowering the forward end of the stack of sheets; Fig. 14 is an enlarged detail end elevation of parts of the sheet feeding mechanism and of associated parts; and Fig. 15 is a section taken on the line 15—15 of Fig. 14.

For the purpose of illustrating the principle of the control mechanism of the present invention it is shown embodied in a duplicating machine of usual construction provided with interleaving devices cooperating with the sheet delivery means of the duplicating machine to place a separator or blotter on each delivered sheet to separate it from the next succeeding sheet. The sheet delivery means of the duplicating machine as shown in the drawings comprises a cylinder 57 for holding the stencil or other printing means and an impression roller 56. The cylinder 57 is mounted on trunnions 3 in the upper part of the side walls 4 of the frame of the machine. Power may be applied to turn the cylinder to perform the printing operation by means of the handle 7 fixed on the outer end of a shaft 13 on which is mounted a gear 14 which meshes with the gear 19 connected with the cylinder. The relative sizes of the gears 14 and 19 are such that the cylinder makes one revolution while the handle 7 is rotated twice.

As the sheets to be printed are fed between the cylinder and impression roller they pass over a feed table 27 supported from the frame of the machine. The sheets may be fed into the machine by hand, or automatically by the feed rolls 30 in the manner which is usual in machines of this type. The means for cooperating with the feed rolls 30 to feed the sheets successively over the feed table 27 into the sheet delivery means are fully described in U. S. Letters 105 110

Patent No. 1,054,399 of February 25, 1913, and may be briefly described as comprising the shaft 33 on which the feed rolls are mounted, driven from the gear 14 in timed relation with the other movements of the machine. A roll 34 carried by a yoke pivoted on the transverse rod 35 acts to hold the sheet of paper down against the feed rolls 30.

10 The pile or stack of sheet paper from which the feed rolls 30 successively remove the uppermost sheet is supported on a table 75 pivotally supported at its rear end on the transverse stud 76. The free forward 15 end of the table 75 is raised, to present the topmost sheet to engagement by the feed rolls, and is then lowered again by means of the arm 77 mounted on the transverse shaft 47. The free end of the arm 77 has a sliding connection with the under side of the table 75 at the point 79 to permit relative movement between the two parts. The shaft 47 is oscillated to raise and lower the forward end of the table 75 by means shown 20 in detail in Fig. 13 and consisting of the arm 80 carrying on its free end the roll 81 held in engagement with the periphery of the cam 82 mounted on the cam shaft 83 journaled on its opposite ends in the machine 25 frame. On the shaft 83 is mounted a gear 84 which receives its actuation from the gear 14 through the intermediate gears 85. The cam roll 81 is held against the periphery of the cam 82 by means of a spring 86 fixed at 30 one end to the machine frame and at the other end to an arm 87 secured to the shaft 47.

35 The forward edge of the pile or stack of sheets on the table 75 bears against a vertically arranged plate 48 having at its upper edge a rearwardly extending lip 88 adapted to engage with the forward end of the topmost sheet. The plate 48 is mounted to reciprocate vertically on the vertically arranged support 89 secured to the machine frame. The plate 48 is arranged to move upwardly with the forward end of the table 75 until the topmost sheet is in position to be engaged and detached by the feed rolls 30 40 and then the plate 48 continues its upward movement to permit the detachment of the uppermost sheet from the pile and its delivery to the cylinder and impression roller. If the plate 48 is prevented from rising, as 45 by the exhaustion of separators as herein-after described, the forward end of the plate 75 is prevented from rising and no sheet will be fed to the cylinder. The means for raising and lowering the plate 48 operate as 50 usual in machines of this type and comprise a cam 90 mounted on the cam shaft 83 and engaging a roll 91 carried by the free end of an arm 92 fixed on a shaft 93 journaled at its ends in the machine frame. Also fixed on the shaft 93 are two arms 94 the rear free

ends of which are pivotally connected with the lower end of the plate 48. The plate 48 is positively moved downward to bring the lip 88 thereof in engagement with the top of the pile of sheets by means of the cam 70 90 and is yieldingly raised by means of the torsion spring 95 encircling the shaft 93 and bearing at one end under one of the arms 94 and fixed at the other end to the machine frame.

75 The means for holding a stack or collection of separators and for detaching a single separator therefrom comprises a vertically arranged magazine 5 adapted to hold the separators and mechanism to remove a single 80 separator. The magazine 5 is mounted on the frame 8 supported from the duplicating machine by the side pieces 11. The stack of separators rest on the bottom 2 of the magazine 5 and the lower end of the stack of separators is held in place by a catch or stop 6. The outermost separator is removed from the stack by means of a gripping member 10 arranged to move into and out of contact with the stack of separators to lift 90 the outermost separator upward against a spring 9 and then free itself from the separator to permit the spring 9 to force the separator downwardly onto the receptacle 12 where it will be in position to be pushed over onto the printed sheet which has just 95 been delivered to separate it from the next delivered sheet. The gripping member 10 is mounted on the yoke 15 movable by the arm 16 of a bell crank carried by a shaft 100 17 journaled in the frame 8. The yoke 15 is pivotally mounted on the arms 16 and is yieldingly connected therewith by the spring 108. The shaft 17 is oscillated by a connection 18 with a crank pin on a cam 26 105 mounted on the shaft 219 of the duplicating machine which receives its actuation through gear connections with the cam shaft 83. It is thus seen that the gripping member 10 is actuated to elevate and detach a separator 110 from the stack at the proper time with respect to the delivery of a sheet onto the receptacle 12.

115 After the gripping member 10 has raised the outermost separator against the spring 9 it is moved out of contact therewith to permit the separator to be pushed downwardly by the spring 9, and for this purpose the yoke 15 carries a roll 28 which contacts with the cam 29 fixed on the frame 8. When 120 the upper end of the yoke 15 has been moved outwardly to free the gripping member 10 from the separator it is held away from the separator as it descends into position to engage the next separator by means of a latch 125 65, pivoted on the frame 8, which engages with a pin 70 carried by the yoke 15. As the yoke 15 rises the pin 70 travels along the under surface of the latch 65, the spring 64 permitting the latch to yield, and then 130

snapping the recessed part 71 of the latch downwardly onto the pin 70 to hold the gripping member from the separators after the cam 29 forces the upper end of the yoke 15 outwardly. The gripping member 10 is held away from the outermost separator sufficiently long to permit the latter to descend, but by the time the separator has fallen and the next succeeding separator is to be raised, the downward movement of the yoke 15 disengages the pin 70 from the notch 71 (under the conditions hereinafter described) so that the gripping member 10 may engage the next separator.

The means for placing the separator on the delivered sheet are shown as consisting of a plunger 20 carried by the free end of an arm 21 mounted on a shaft 22, the plunger being arranged so as to pass through an alined hole formed in the stack of separators. The shaft 22 is mounted on the frame 8 and is provided with a crank 23 connected by a spring pressed link 24 to the lower end of an arm 25 pivoted on the machine frame and provided with a roll 78 adapted to be engaged by the periphery of the cam 26. The construction is such that as a sheet is delivered onto the receptacle 12 and a separator drops, the plunger 20 is actuated by the spring-pressed link 24 to push the fallen separator onto the delivered sheet, by striking the separator above the hole therein. The plunger 20 is returned to inoperative position through the engagement of the roll 78 by the active part of the cam 26. An arm 32 spring pressed by the arm 31 pivoted on an arm mounted on the shaft 17 forces the lower end of the stack of separators against the stop 6 after a separator has been raised by the gripping member 10 to permit it to fall outside the stop, and then as the gripping member moves into position to engage the next separator, the oscillation of shaft 17 causes the arm 31 to be freed from the arm 32, as shown in Fig. 6, to permit the ready lifting of the outermost separator by the gripping member.

The mechanism to stop the feeding and so the delivery of sheets when the supply of separators has been exhausted, comprises a lug 36 mounted on the yoke 15 and adapted to ride free when the gripping member 10 encounters a separator on the inward and upward movement of the yoke 15, and to engage the lower end of a movable rod 37 mounted on the frame 8 when the gripping member 10 does not encounter a separator. On the upper end of the vertically movable rod 37 rests the free end of an arm 38 of a bell crank fixed on the shaft 39 journaled in brackets on the frame 8. The other arm 40 of the bell crank is pivotally connected by a link 41 with one arm of a bell crank 42 fulcrumed on the frame 8 and connected

by a link 43 with the dog 44 of a stop lock. The stop lock comprises the dog 44 pivoted at 45 on the plate 48 of the sheet feeding mechanism, the shaft 47 which acts as a stop, and the spring 46 which forces the notched upper end of the dog 44 under the shaft 47 when on the exhaustion of separators the lug 36 engages with the lower end of the rod 37 and raises the arm 38 until the end of the arm 40 to which the link 41 is connected is over dead center. The operation just described is clearly shown in Figs. 6 and 7, and Figs. 9 and 10. While the notched end of the dog 44 is in engagement with the shaft 47 the plate 48 is prevented from rising and consequently no sheets can be fed by the rolls 30 to the cylinder. To replenish the receptacle 5 with separators the operator lifts the free end of the spring 9 which is mounted on a yoke 115 pivoted on the shaft 39. Within the yoke of the spring 9 is a second yoke 116 fixed on the shaft 39. The yokes 115 and 116 are provided with outwardly extending handle parts. When the magazine 5 has been replenished with separators, the operator manually turns the yoke 116 thereby turning the shaft 39 and returning the arm 38 to normal position resting on top of the upper end of the rod 37, and simultaneously therewith moving the spring 9 to normal position. The turning of the shaft 39 to bring the arm 38 into engagement with the rod 37 throws the arm 40 over dead center and thereby disengages the notched end of the dog 44 from the shaft 47, which permits the plate 48 to rise.

While each sheet is on the feed table 27 and before it is fed to the sheet delivery means, that is, to the cylinder 57 and impression roller 56, a series of sheet feeling fingers 96 pass up through holes in the feed table 27 to determine whether a sheet is on the feed table. The sheet feeling fingers 96 are mounted on a transverse shaft 97 journaled at its ends in the machine frame. Fixed on the shaft 97 is a downwardly extending arm 120 carrying on its free lower end a roll 119 adapted to travel against the periphery of the cam 117 mounted on the shaft 83. A light contraction spring 121 secured at one end to the hub part of the arm 120 and at its other end to a fixed part of the machine holds the roll 119 against the periphery of the cam 117. When the flat part of the cam 117 moves opposite the roll 119 the spring 121 is free to turn the shaft 97 to bring the fingers 96 into position to perform their sheet feeling function. If the fingers 96 encounter a sheet and are held thereby the impression roller 56 is permitted to press the sheet up against the cylinder 57. If, however, the fingers 96 do not encounter a sheet on the feed table they will pass upwardly through alined holes in the plate 110 and as a result the impression roller 56 will

be held away from the cylinder 57 by the following elements:—

A cradle 103 in the form of a yoke is pivotally mounted on a stud 102 fixed in the machine frame. Also pivotally mounted on the stud 102 is an arm 101 yieldingly connected with the cradle 103 by the spring 104. On its free end the arm 101 carries the roll 100 adapted to be engaged by the cam 99 mounted on the shaft 83 to oscillate the arm 101 and cradle 103 in a counter-clockwise direction, viewing Fig. 15. One of the arms of the cradle 103 carries a pin 105 received in a slot in the lower end of an arm 106 fixed to a collar 107 loosely mounted on the shaft 97. One end of a torsion spring 98 enters the collar 107 and the other end is received in a slot in a collar 118 fixed on the shaft 97. The torsion spring 98 functions to swing the cradle 103 (through the arm 106) in a clockwise direction when the flat part 109 of the cam 99 is opposite the roll 100 and a sheet of paper on the table 27 holds the fingers 96 depressed. If no sheet is on the table 27 permitting the spring 121 to oscillate the shaft 97 to move the fingers 96 up through the holes in the table 27 the lug or stop 122 carried by the arm 106 will engage with the lug 123 on the hub of the arm 120, and thus the spring 98 will be prevented from turning the cradle 103. When the cradle 103 is thus held the impression roller 56 is prevented from moving into engagement with the cylinder 57 as will appear hereinafter.

The mechanism to stop the operation of the separator placing devices when no sheet is on the feed table 27 in position to be fed between the cylinder 57 and impression roller 56 comprises the following:—Mounted on the cylinder of the duplicating machine are cams 49 and 50 arranged to coact with a roll 51 mounted on an arm 52 fixed on a shaft 53 extending transversely of the machine and carrying on its other end a lever 54. The arm 52 and the short arm of the lever 54 both rest upon the free ends of the lever arms 58 which carry the impression roller 56 and are fulcrumed on the machine frame at 59. Thus the engagement of the roll 51 by either the cam 49 or cam 50 depresses the impression roller 56 and oscillates the lever 54 to raise the rear flattened end 113 thereof to permit the platform 111 of the cradle 103 to swing thereunder when the sheet feeling fingers 96 encounter no sheet on the feed table 27 during their upward travel, as shown in Fig. 11. The impression roller 56 is yieldingly forced toward the periphery of the cylinder 57 by means of the spring 114.

The cam 50 is so positioned relative to the timing of the movements of the shafts 97 and 83, that when the shaft 53 has been oscillated to raise the end 113 of the lever

54 and the cradle 103 has swung under the lever 54 (when no sheet is present on the feed table 27), the disengagement of the cam 50 from the roll 51 puts the lever 54 under action of the spring 114 and the flattened end 113 of the lever 54 is held on the table 111 of the cradle 103, thereby preventing the impression roller from moving into contact with the periphery of the cylinder 57 and at the same time preventing the operation of the interleaving devices. For this latter purpose one of the arms 58 has fixed thereto a downwardly extending arm 60 (Fig. 1) pivotally connected by the link 61 with the lower end of a lever 62 pivoted at 63 on the frame 8. Pivoted at 67 on an upward extension of the latch 65 is a pawl 66 provided with a manually operated screw 68 adapted to hold it in alternate positions on the latch 65. During the normal operation of the duplicating machine and of the interleaving devices the pawl 66 has the position shown in Fig. 5. In this position the lower end of the pawl 66 is adapted to engage the upper offset end of the lever 62 when a sheet 90 on the feed table has been engaged by the feeling fingers, thereby permitting the impression roller 56 to move upwardly to force the sheet against the periphery of the cylinder. When no sheet is on the feed table, as 95 a result of which the cradle 103 is held in position to prevent the downward movement of the long arm of the lever 54 and thereby hold the impression roller away from the cylinder 57, the upper end of the lever 62 100 is held in the position shown in Fig. 1, so that the lower end of the pawl 66 does not encounter it on the downward movement of the latch 65.

When sheets are fed successively over the feed table 27 to the sheet delivery means, so that after each depression of the impression roller 56 it rises again to force the sheet against the cylinder 57, thereby oscillating the arms 58 and 60 in a clockwise direction (viewing Fig. 1) the lever 62 is swung into position to engage the pawl 66 on the downward movement of the yoke 15 and of the pawl 66 therewith under the action of the spring 64. When the pawl 66 encounters 115 the upper end of the lever 62 the latch 65 is arrested and the continued downward movement of the yoke 15 frees the pin 70 from the notch 71 and permits the yoke to move toward the supply of separators 120 under the action of the spring 108 and bring the gripping member into engagement with the outermost separator. On the upward movement of the yoke 15 during the lifting of the outermost separator, the pin 70 travels 125 along the lower surface of the latch 65 lifting the latch against the action of its spring 64. Then when the yoke 15 is forced outward by reason of the contact of the roll 28 with the cam 29 the pin 70 enters the notch 130

71 and the gripping member 10 is held from engagement with the separators until the yoke again reaches nearly the limit of its downward movement and the pin 70 is disconnected from the notch 71 by the engagement of the pawl 66 with the lever 62. When no sheet is on the feed table in position to be fed to the sheet delivery means, and as a result thereof the impression roller 56 is held depressed and the lever 62 is held in the position shown in Fig. 1, the pawl 66 on the downward movement of the latch 65 with the yoke 15 passes by the upper end of the lever 62, and consequently the latch 65 under the action of the spring 64 holds the notch part 71 in engagement with the pin 70, thereby preventing the yoke 15 from swinging inwardly and bringing the gripping means 10 into engagement with the outermost separator. Hence no separator is detached from the stack of separators in the receptacle 5 and placed in the receptacle 12 when no sheet is fed into and delivered by the sheet delivery means.

25 When it is desired to operate the duplicating machine without placing a separator on each sheet as it is delivered, the screw 68 will be removed from the hole occupied in holding the latch during the normal operation of the machine in which a separator is placed on each delivered sheet, and inserted in the hole 69, thereby preventing the pawl 66 from engaging with the lever 62. Thus the yoke 15 is held away from the stack 35 of separators during such times as it is desired to run the duplicating machine without interleaving the delivered sheets.

To prevent the plunger 20 from movement while no separator is to be delivered, the lower extension of the lever 62 is pivotally connected by a link 72 with a locking pawl 73 cooperating with a pawl lock 74 fastened on the shaft 22 carrying the arm 21 on which the plunger 20 is mounted, as shown in Fig. 40 1. The clockwise movement of the lever 62 imparted to it when the impression roller 56 is permitted to rise to press a sheet against the cylinder 57, pulls the link 72 to the left, viewing Fig. 1, and thereby disengages the pawl 73 from the notch 55 of the lock 74 to permit the shaft 22 to be oscillated by the cam 26. A spring 112 holds the pawl 73 down on the lock 74.

Having thus described the invention what I claim as new is:—

1. A control mechanism for duplicating machines provided with means for delivering sheets successively, means for determining whether a sheet is in position to be fed to the sheet delivery means, means for holding a collection of separators, and means for placing a separator on each delivered sheet, comprising, means operative upon the exhaustion of separators for preventing the operation of the sheet delivery means, and

means for preventing the operation of the separator placing means when no sheet is in position to be fed to the sheet delivery means.

2. A control mechanism for duplicating machines provided with means for delivering sheets successively, means for holding a collection of separators, and means for placing a separator on each delivered sheet, comprising, means operative upon the exhaustion of separators to prevent the operation of the sheet delivery means.

3. A control mechanism for duplicating machines provided with means for delivering sheets successively, means for determining whether a sheet is in position to be fed to the sheet delivery means, and means for placing a separator on each delivered sheet, comprising, means for preventing the operation of the separator placing means when no sheet is in position to be fed to the sheet delivery means.

4. A control mechanism for duplicating machines provided with means for delivering sheets successively, and means for placing a separator on each delivered sheet, comprising, means for preventing the operation of the separator placing means to permit the delivery of sheets without the placing of separators on the delivered sheets.

5. In a duplicating machine having means for delivering sheets successively, sheet feeling means for determining whether a sheet is in position to be fed to the delivery means, means for holding a collection of separators, and means for placing a separator on each delivered sheet including gripping means for engaging the outermost separator, means controlled by the sheet feeling means for preventing the gripping means from engaging the outermost separator when no sheet is in position to be fed to the delivery means.

6. In a duplicating machine having means for delivering sheets successively, sheet feeling means for determining whether a sheet is in position to be fed to the delivery means, means for holding a collection of separators and means for placing a separator on each delivered sheet, means controlled by the sheet feeling means for preventing the operation of the separator placing means when no sheet is in position to be fed to the delivery means.

7. In a duplicating machine having means for delivering sheets successively, sheet feeling means for determining whether a sheet is in position to be fed to the delivery means, means for holding a collection of separators, and means for placing a separator on each delivered sheet including a separator gripping means and means for alternately bringing the gripping means into and out of contact with the outermost separator, means controlled by the sheet feeling means when

no sheet is in position to be fed to the delivery means for holding the separator gripping means out of contact with the separators.

- 5 8. In a duplicating machine having means for delivering sheets successively, sheet feeling means for determining whether a sheet is in position to be fed to the delivery means, and means for placing a separator on each 10 delivered sheet including a rock shaft and a plunger arm mounted on the rock shaft for positively pushing a separator onto a delivered sheet, means controlled by the sheet feeling means when no sheet is in position to be fed to the delivery means for preventing the rock shaft from oscillation.
- 15 9. In a duplicating machine having means for delivering sheets successively, sheet feeling means for determining whether a sheet 20 is in position to be fed to the sheet delivery means, means for holding a stack of separators, and means for placing a separator on each delivered sheet including a separator gripping means mounted to move into and 25 out of contact with the outermost separator, means controlled by the sheet feeling means when no sheet is in position to be fed to the sheet delivery means for preventing the operation of the separator gripping means, 30 comprising, a lever, a cradle moved by the sheet feeling means to lock the lever, a second lever, connections between the two levers, a latch for holding the gripping means from the separators, and a pawl connected with the latch and normally engaging 35 the second lever on the movement of the separator gripping means to release the latch from the gripping means, said pawl being held from contact with the second 40 lever when the first lever is locked by the sheet feeling means.
10. In a duplicating machine having means for delivering sheets successively, sheet feeling means for determining whether 45 a sheet is in position to be fed to the sheet delivery means, means for holding a stack of separators, and means for placing a separator on each delivered sheet including a separator gripping means mounted to move 50 into and out of contact with the outermost separator and an oscillatory plunger for pushing a separator onto a delivered sheet, means controlled by the sheet feeling means when no sheet is in position to be fed to the sheet delivery means for preventing the operation of the separator gripping means and of the plunger, comprising, a lever, a cradle moved by the sheet feeling means to lock the lever, a second lever, connections between the two levers, a latch for holding the gripping means from the separators, a pawl connected with the latch and normally engaging 55 the second lever on the movement of the separator gripping means to release the latch from the gripping means, said

pawl being held from contact with the second lever when the first lever is locked by the sheet feeling means, and a latch pawl operated by the second lever for holding the plunger from operation.

11. In a duplicating machine having means for delivering sheets successively, sheet feeling means for determining whether a sheet is in position to be fed to the sheet delivery means, means for holding a collection of separators, means for placing a separator on each delivered sheet including a yoke carrying a separator gripping means and mounted to move upwardly into contact with the outermost separator and downwardly out of contact therewith, a pin on the yoke, a latch spring-pressed into engagement with the pin as the yoke rises, a recess in the yoke for receiving the pin, means for forcing the yoke outward to permit the pin to enter the recess and a pawl mounted on the latch, means controlled by the sheet feeling means for permitting the pin to remain in the recess of the latch when no sheet is in position to be fed to the sheet delivery means and for detaching the pin from the recess when a sheet is in position to be fed to the sheet delivery means, comprising a lever and means controlled by the sheet feeling means to hold the lever in the path of the pawl when a sheet is in position to be fed to the delivery means and to hold the lever out of the path of the pawl when no sheet is in position to be fed to the delivery means.

12. In a duplicating machine having means for delivering sheets successively, means for holding a stack of separators, and means for placing a separator on each delivered sheet including an arm movable toward and from the stack of separators and gripping means mounted on the arm for contacting with the outermost separator, a movable member normally stationary, a lock arranged to hold the sheet delivery means inoperative, means for operating the lock arranged to be actuated by the movable member, and means mounted on the arm of the separator placing means for actuating the movable member when the gripping means on the inward movement of the arm moves to a position permitted by the exhaustion of separators.

13. In a duplicating machine having means for delivering sheets successively, means for holding a stack of separators, and means for placing a separator on each delivered sheet, means controlled by the separator placing means for preventing the operation of the sheet delivery means comprising a movable member normally stationary, a stop, a latch connected with the sheet delivery means, means arranged to be actuated by the movable member for moving the latch into engagement with the stop to

prevent the action of the sheet delivery means, and means connected with the separator placing means for actuating the movable member on the exhaustion of separators.

14. In a duplicating machine having means for delivering sheets successively including a vertically movable member, means for holding a stack of separators, and means for placing a separator on each delivered sheet, a stop, a latch connected with the vertically movable member, a movable rod normally stationary, means arranged to be actuated by the rod to move the latch into engagement with the stop to hold the member from moving and thereby prevent the operation of the sheet delivery means, and means connected with the separator placing means for actuating the rod on the exhaustion of separators.

15. In a duplicating machine having means for delivering sheets successively, means for holding a stack of separators and means for placing a separator on each delivered sheet, a stop, a latch connected with the sheet delivery means and adapted to en-

gage with the stop to prevent the operation of the sheet delivery means, and means operated by the separator placing means on the exhaustion of separators for moving 30 the latch into engagement with the stop.

16. In a duplicating machine having sheet delivery means, means for holding a collection of separators, and means for placing a separator on each delivered sheet 35 including a gripping member, an arm for supporting the gripping member and means for moving the arm upwardly toward and downwardly from the separators, a stop, a latch connected with the sheet delivery 40 means adapted to engage with the stop to prevent the operation of the sheet delivery means, a movable, vertically arranged rod, a bell crank having an arm resting on the upper end of the rod, connections between the bell crank and the latch, and means carried by the arm arranged to lift the rod on the exhaustion of separators to move the latch into engagement with the stop. 45

ERNEST JOSEPH BRASSEUR.
